UNITED STATES PATENT OFFICE.

JACOB M. LEVINE, OF CLINTON, ILLINOIS.

AUTOMATIC OIL-CUP FOR AIR-PUMPS.

1,249,137.

Specification of Letters Patent.

Patented Dec. 4, 1917.

Application filed November 22, 1916, Serial No. 132,877. Renewed October 15, 1917. Serial No. 196,735.

To all whom it may concern:

Be it known that I, JACOB M. LEVINE, a resident of Clinton, county of DeWitt, and State of Illinois, have invented certain new and useful Improvements in Automatic Oil-Cups for Air-Pumps, of which the following is a specification.

My invention relates to improvements in automatic oil cups and particularly to such devices as are used in connection with the air pumps of locomotives and the like.

The principal object of this invention is the provision of such a device which is automatic in operation and simple in construction, being controlled by the reciprocations of the piston of the air pump to deliver oil into the cylinder thereof at intervals in small quantities, as drop by drop. The air pump controls the operation of the oil cup by means of the variation in the air pressure caused by the reciprocations of the piston.

Another object of this invention is the provision of such a device including a receptacle having a valve member slidably mounted therein with a limited movement and having a passage therethrough, the opening thereto from the receptacle being below the valve proper, the passage being provided with a valve to prevent the passage of air therethrough on the upstroke of the piston of the air pump, the valve member being normally held in closed position on its seat and adapted to be raised by the increased air pressure by the upstroke of the piston, so that a small quantity of oil will pass from the receptacle into the passage through the valve member, the valve in the passage preventing its discharge into the cylinder until the piston takes its down stroke, when a partial vacuum is created and the air pressure in the upper part of the cylinder of the air pump is reduced so that the valve in the passage is unseated and a small quantity or drop of oil is discharged into the cylinder before the piston commences its upstroke.

To the accomplishment of the foregoing and such other objects as may hereinafter appear my invention consists in the construction, combination and arrangement of parts hereinafter described and then sought to be defined in the appended claims reference being had to the accompanying drawings forming a part hereof and which shows merely for the purpose of illustrative dis-

closure a preferred embodiment of my invention, it being expressly understood that various changes may be made in practice within the scope of the claims without dis- 60 gressing from my inventive idea.

In the drawing, the figure represents a vertical cross section taken through a device constructed according to my invention, the open or raised position of the valve member 65 being indicated in dotted lines.

Referring now to the drawing, the numeral 1 designates the body of the device which is in the form of a hollow casing or cylindrical receptacle 2, having its lower or 70 bottom portion reduced, as at 3, and provided with a passage 4 therethrough, and having the valve seat 5 provided at its upper end. The lower end part of the reduced portion of the body is externally screw 75 threaded as at 6 for convenient attachment to the usual air pump of a locomotive, the reduced portion being squared so as to facilitate the use of a wrench or other tool.

Slidably mounted in the passage 4 is the 80 valve member 7, having the valve proper 8 in its upper portion adapted to rest on the valve seat 5. Depending from the valve proper is the stem portion 9, having an intermediate reduced annular portion 10 to 85 receive the engaging end 11 of the locking screw 12, the reduced annular portion being considerably longer than the width of the end of the screw so that the valve member has a limited movement within the passage 90 4, whereby the valve 8 may be raised from off its seat.

The stem portion 9 of the valve member is provided with the longitudinal passage 13 therein, which is enlarged near the lower 95 end thereof, as at 14, to make provision for the gravity actuated ball valve 15 and its seat 16, the ball valve being held for limited movement within the enlarged passage 14 by means of the pin 17. The passage 13 100 in the valve member communicates with the receptacle or casing when the valve 8 is off its seat by means of the horizontally extending passage 18, the opening into which is located immediately below the valve 8. 105

The body of the device is internally screw-threaded, as at 19, to receive the cap member 20, which has the depending stud or stem 21 to hold the coil spring 22, which embraces it, and the other end of which embraces and 110 engages the stud or projection 23 on the upper end of the valve member 7 above the

valve proper 8, so as to normally hold the valve on its seat and to force it to its closed position when the air pressure is decreased sufficiently.

5 The operation of the device is as follows, it being understood that the casing or receptacle has a quantity of oil or other lubricant therein, and that the parts are normally in the position shown in full lines.

10 On the upstroke of the piston of the air pump, the increase in the pressure of the air thereabove forces the ball valve 15 against its seat 16 and prevents the passage of any air through the passage 13 into the casing or receptacle. This increased air pressure is sufficient to overcome the downward pressure of the spring 22 against the valve member 7 and therefore forces the valve member 7 upwardly, lifting the valve 8 off its seat 16 and permitting a small quantity of oil to enter passage 13 through passage 18. On the return or downward stroke of the piston of the air pump, a partial vacuum is created in the upper portion of the cylinder thereof, decreasing the air pressure so that the spring 22 forces the valve member 7 downwardly to seat the valve proper 8, and also permitting the ball valve 15 to drop from its seat so that a small quantity or drop of oil will be discharged from the passage 13 into the air pump before the piston starts its next upward stroke, thereby completing the cycle of operation.

What I claim is:—

- 35 1. A device of the character described including in combination, a receptacle having an outlet passage, a valve member movably mounted in said outlet passage and having a discharge passage therethrough communicating with the receptacle when the valve member is opened, and a valve for said discharge passage arranged so as to close said passage when said valve member is opened.
- 40 2. A device of the character described including in combination, a receptacle adapted to be mounted on a reciprocating pump and having an outlet passage, a valve member movably mounted in said outlet passage, means for limiting the movement of said valve member in said passage, said valve member having a discharge passage therethrough adapted to communicate with the receptacle when the valve member is open, means for normally holding said valve member closed, and a valve for said discharge passage, said valve member being adapted to be raised for opening on the compression stroke of the pump, the increased air pressure closing the valve in the discharge passage, the valve member closing on the suction stroke of the air pump and the valve in the discharge passage opening.
- 45 3. A device of the character described including in combination, a receptacle having an outlet passage provided with a valve

seat, a valve member mounted in said outlet passage and having a limited sliding movement therein and adapted to fit said valve seat, means for normally holding said valve member on its seat, said valve being adapted to be forced open on the compression stroke of the pump to which the device is attached, said valve member having a discharge passage therethrough which communicates with said receptacle and having a valve therefor which is normally open but is adapted to be closed on the compression stroke of the pump.

4. A device of the character described including in combination, a receptacle having an outlet passage provided with a valve seat, a valve member mounted in said outlet passage and having a limited sliding movement therein, said valve member having a valve proper adapted to fit said valve seat, means for normally holding said valve proper on its seat, said valve member having a discharge passage therethrough with an outlet adapted to communicate with the receptacle when the valve is open, said outlet being located below said valve proper, and a valve in said discharge passage.

5. A device of the character described including in combination, a receptacle having an outlet passage provided with a valve seat, a valve member mounted in said outlet passage and having a limited sliding movement therein, said valve member having a valve proper adapted to fit said valve seat, means for normally holding said valve proper on its seat, said valve member having a discharge passage therethrough with its communicating outlet to the receptacle located below said valve proper, and a gravity actuated valve in said discharge passage arranged so as to normally open.

6. A device of the character described including in combination, a receptacle having an outlet passage provided with a valve seat, a valve member mounted in said outlet passage and having a limited sliding movement therein, said valve member having a valve proper adapted to fit said valve seat, means for normally holding said valve proper on its seat, said valve member having a discharge passage therethrough having a laterally extending inlet passage located below said valve proper so as to be placed in communication with said receptacle when the valve proper is off its seat, and a gravity actuated valve in said discharge passage arranged so as to be normally open.

7. A device of the character described including in combination, a receptacle having a reduced outlet portion with a passage therethrough having a valve seat, a valve member movably mounted in said passage and having a reduced annular portion and a valve proper fitting said valve seat, an element in said reduced outlet portion with

its end engaging said annular portion of the valve member so as to limit its movement, a cap member for said receptacle, a spring bearing against said cap member and said 5 valve member for normally holding said valve proper on its seat, said valve member having a discharge passage therethrough having its inlet opening into said receptacle located below said valve proper, and a valve 10 in said discharge passage.

8. A device of the character described including in combination, a receptacle having a reduced outlet portion with a passage therethrough having a valve seat, a valve 15 member movably mounted in said passage and having a reduced portion and a valve proper fitting said valve seat, an element in said reduced outlet portion with its end engaging said reduced annular portion of the 20 valve member so as to limit its movement, a cap member for said receptacle, a spring bearing against said cap member and said valve member for normally holding said valve proper on its seat, said valve member

having a discharge passage therethrough 25 having its inlet opening into said receptacle located below said valve proper, and a gravity actuated valve in said discharge passage arranged so as to be normally open and to be closed when subjected to the increased 30 pressure which opens said valve proper.

9. A device of the character described including in combination, a receptacle having an outlet passage and a valve seat at its inner end, a valve member movably mounted 35 in said passage and having a valve proper at its inner end for said valve seat, said valve member having a discharge passage therethrough communicating with said receptacle when said valve proper is off its seat, 40 and a valve in said discharge passage arranged so as to close when said valve proper is off its seat so that a charge of fluid is admitted into the discharge passage, which is discharged when the valve proper is seated 45 and the valve in the discharge passage opens.

JACOB M. LEVINE.
